CLAIM

The ornamental design for an automatic feeder for animals, including livestock, household pets, and aquatic life, as shown and described.

DESCRIPTION

FIG. 1 is a perspective view of an automatic feeder for animals, including livestock, household pets, and aquatic life showing our new design;

FIG. 2 is an enlarged front elevational view thereof;

FIG. 3 is a rear elevational view thereof;

FIG. 4 is a bottom plan view thereof;

FIG. 5 is a top plan view thereof; and,

FIG. 6 is a side elevational view thereof, the side opposite being a mirror image of the side shown.

FIG. 1

FIG. 5

FIG. 3

FIG. 2

FIG. 4

FIG. 6
